UNITED STATES PATENT OFFICE.

JAMES WORRALL, OF ORDSALL, SALFORD, COUNTY OF LANCASTER, AND
JOHN KERSHAW, OF HEBDEN BRIDGE, COUNTY OF YORK, ENGLAND.

MACHINE FOR BRUSHING AND NAPPING FABRICS.

SPECIFICATION forming part of Letters Patent No. 406,187, dated July 2, 1889.

Application filed September 25, 1888. Serial No. 286,326. (No model.) Patented in England December 13, 1887, No. 17,143; in France August 18, 1888, No. 192,479, and in Germany August 30, 1888, No. 46,347.

To all whom it may concern:

Be it known that we, JAMES WORRALL, of Ordsall, Salford, in the county of Lancaster, England, and JOHN KERSHAW, of Hebden Bridge, in the county of York, England, have invented certain new and useful Improvements in Machines for Brushing and Napping Fabrics, (for which we have obtained Letters Patent of Great Britain, No. 17,143, dated December 13, 1887; brevet d'invention of the Republic of France, No. 192,479, dated August 18, 1888, and patent of the Empire of Germany, No. 46,347, dated August 30, 1888,) of which the following is a specification.

This invention relates chiefly to the finishing of cords, moleskins, and velveteens; but it is also applicable to the treatment of other fabrics in which a nap is required to be raised on the same.

In finishing corduroys it has been usual to subject the cut-pile fabric, as it is passed through the finishing-machine, to the action of reciprocating brushes or endless chains of brushes working transversely of the machine, and at right angles to the travel of the fabric. Great difficulty has, however, been found in insuring that the brushes shall penetrate to the bottom of the pile, or that they shall act uniformly on the whole breadth of the fabric.

Now the main object of the present invention is to obtain a uniform action of the brushes over the surface of the fabric, and that of a more searching character than heretofore.

To this end we construct the finishing-machine in such a manner that the cord or other fabric will be fed into the machine at the side thereof, instead of at the front end, as heretofore, and received onto the rounded edge of a diagonal bed or bar stretching from side to side of the machine. Over this bed the fabric is drawn by a suitable card-roller, and it is delivered out of the machine at the back end thereof. In front of this diagonal bed we mount a rotary brush, the tufts of which are helically disposed in the usual manner around its periphery. To this brush we give

a rapid rotary motion, and we thereby cause it to act efficiently on the fabric as it is strained over the rounded edge of the diagonal bed or bar. In traveling over this rounded edge a space is opened out in the pile for the brush to enter and act upon the whole length of the pile. When a corded fabric is thus submitted to the action of the rotating brush, the cords will, when the cords extend in the direction of the filling, lie nearly parallel to the edge of the bed, and therefore the ground of the fabric will be laid bare as it passes over the edge of the bed. No obstacle will therefore be presented to the penetration of the brush into the pile, and hence the brushing will be rendered far more efficient than heretofore. When it is desired to raise a nap on the fabric, a card-roller is substituted for the rotary brush.

In the accompanying drawings, Figure 1 shows in plan view our improved machine fitted as a finishing-machine, say, for brushing cords; and Fig. 2 is a front view of the same, the bars which guide the cloth into the machine being removed, the better to illustrate the construction and position of the working parts. Fig. 3 shows in front view the guide-bars mounted on the framing of the machine, together with a guide-roller for receiving the cloth from the bars, and Fig. 4 is an end elevation of the same. Figs. 5, 6, and 7 are detached views illustrating the arrangement of the diagonal bed or bar over which the cloth travels and the parts in immediate connection therewith for brushing the cloth, and for insuring that the cloth shall retain its proper position while passing over the bar.

A A' are the side frames of the machine, held together by tie-rods and furnished with bearings for the main driving-shaft B.

C C are light standards mounted on a lateral extension of the frame A and carrying guide-bars c c' c² c³, the position of the standards being such that the guide-bars will lie askew, or at about an angle of thirty degrees with the side frame A. To the lateral extension of this side frame bracket-bearings are

bolted to carry a guide-roller D, which is fitted with a friction-pulley d, operated upon by a brake-band o, passing about the pulley and maintained taut by a weight p. The friction-pulley will retard the tendency of the roller to rotate under the draft of the cloth that is submitted to the action of the machine.

E is a diagonal bed or bar made fast by brackets to the side frames A A'. This bar, which lies at an angle to the frame A corresponding to the angle made by the guide-bars with that frame, serves to present the cloth to the action of the rotary finishing-brush F, which is mounted in bearings attached to the side frames, the bracket of the side frame A being the same as that which carries the front end of the diagonal bar. This same bracket also carries a bearing for a short smoothing-roller G, which underlies the bar E and is supported at its farther end in a bearing carried by the bar.

H is a roller for drawing the cloth over the diagonal bar, whence the cloth passes under a guide-roller h and up to a roller I, which delivers it to the ordinary reciprocating folder K.

The cloth to be treated is brought in a pile to the side of the machine and laid alternately over and under the guide-bars c c' c² c³, as shown in Fig. 4. It then passes under the guide-roller D to the under side of the diagonal bed or bar E, and, being laid over the edge thereof, it is brought up to the drawing-roller H, whence it passes, as already stated, under the roller h, and thence to the folder.

The driving-shaft B is fitted with fast and loose band-pulleys b, through which it receives its motion. It is also fitted with a band-pulley b' and a double-grooved band-pulley b² for transmitting motion to the operating parts of the mechanism. A crossed band from the pulley b' passes round a pulley h', running loosely on the shaft of the roller H. Cast in one with this pulley is a spur-pinion h², which gears into a spur-wheel h³, keyed to a transverse axle h⁴, carried by bearings on the side frames A A'. To the opposite end of this axle is keyed a spur-pinion h⁵, gearing into a spur-wheel h⁶, which is keyed to the axle of the roller H. This arrangement of gearing serves to transmit from the quickly-rotating driving-shaft B a slow rotary motion to the roller H, for the purpose of drawing the cloth into and through the machine.

Keyed to the front end of the axle of the brush F is a band-pulley f, which receives a band from the double-grooved pulley b² in the following manner.

f' f² are guide-pulleys mounted on studs of the side frame A, and f³ is an adjustable tension-pulley carried by a stud, which is adjustable by hand in a longitudinal slot f⁹ in the frame A, and secured in position by any suitable clamping device—such, for instance, as a nut. A band from the pulley b² passes under the guide-pulley f', then up to and over

the pulley f, down to and under the guide-pulley f², and thence to the second groove of the pulley b². From this pulley the band passes forward to the tension-pulley f³ and back to the pulley b². Thus provision is made for the band to accommodate itself to the skewed position of the brush-shaft. On the opposite end of the brush-shaft is keyed a worm f⁴, which serves to drive a worm-wheel g, carried by a short shaft that has its bearings on the bracket that connects with the frame A' and carries the brush-shaft.

g' is a grooved pulley on the worm-wheel shaft, and from it passes a band which leads to a pair of grooved pulleys g², carried by an adjustable stud connected to a standard supported on the near bearing of the brush-shaft. The said stud is adjustable by hand in a longitudinal slot g³ in said standard, and may be secured in any desired position by a suitable clamping device—such, for instance, as a nut. From these pulleys the band passes down to and is laid around a grooved pulley on the axle of the smoothing-roller G. Thus a slow rotary motion is imparted to the roller G as the cloth is drawn into the machine. This roller is ribbed longitudinally, and it serves to counteract a tendency which the cloth has to shift on the diagonal bar E away from the feeding side of the machine. A slow rotary motion is given to the delivery-roller I by a band which passes from a pulley h' on the shaft of the roller H to a pulley i on the shaft of the roller I. The folding apparatus K receives its reciprocating motion from the crank k of a transverse shaft k', which is driven by a band from the roller I.

It will now be understood that when corded cloth is presented to the action of the brush F the bristles will, by reason of the opening of the pile, be able to penetrate the sides of the cords and act upon the whole length of the pile.

To adapt the machine to the raising of a pile for the manufacture of mole-skins, it is only necessary to substitute for the brush F a card-roller of any approved construction. When the card-roller is used in this machine, a fuller nap is raised (owing to its diagonal action on the cloth) than if it acted longitudinally of the cloth, and, as compared with cross-raising, its action is far more rapid. The nap may be raised on one or both sides of the fabric, but when required to be raised on the back the fabric will in that case be laid into the machine so that its back shall be presented to the action of the card-roller.

It will be understood that the length of the brush and of the carding-roller will somewhat exceed the measured width of the fabric as presented to the edge of the diagonal bed.

Having now particularly described and ascertained the nature of our said invention and in what manner the same is to be performed, we declare that what we claim is—

1. In a finishing and raising machine, the combination, with a guide-roller for leading in the cloth and a drawing-roller for passing it out of the machine, of a transverse diagonal bed or bar over the edge of which the cloth is drawn, and a rotary finishing-brush or card-roller arranged to work parallel thereto, as and for the purpose above set forth.
2. The combination, with the diagonal bed or bar E, of the smoothing-roller G, and means, substantially as described, for rotating the

said roller, as and for the purpose above set forth.

JAMES WORRALL.
JOHN KERSHAW.
